TOY GUN AND PROJECTILE

Filed Dec. 15, 1925

Fig. 2

Nathaniel Baldwin INVENTOR

UNITED STATES PATENT OFFICE

NATHANIEL BALDWIN, OF EAST MILL CREEK, UTAH

TOY GUN AND PROJECTILE

Application filed December 15, 1925. Serial No. 75,576.

The present invention appertains to toy guns of the class in which elastic cords are used to propel projectiles.

The object of the invention is to provide a simple, inexpensive, and harmless toy of the class above mentioned which will discharge a disc or sheet of light material with a whirling motion.

I attain this and other objects by the structure illustrated in the accompanying drawing in which Fig. 1 is a side view elevation of the loaded gun and Fig. 2 is a top view of the same.

In both figures of the drawing numeral 15 designates the body of the toy made preferably from a piece of thin board cut into the desired form, provided with a perforation 2 and thin slot at the end to receive the elastic cord 3 and having a recess or seat on one 20 side adapted to receive the projectile 4, which may preferably consist of a disc of cardboard or other light material.

After setting the projectile 4 in place in the recess or seat, the elastic cord 3 is stretched 25 over it as shown in the drawing and holds it in place ready for action. The gun body 1 is so formed that when the projectile is in place in the recess or seat a portion of it projects below the body as shown at 5 30 and by pressing the finger against this portion the projectile will be lifted upward until the elastic cord will swing it upward over the corner or lug 6 and forward with a whirling motion.

35 I claim:

1. A toy gun and projectile comprising a gun body to hold the projectile, an elastic cord connected with said gun body to stretch over the projectile, a projectile and a portion 40 of said body being formed to hold said projectile in place against the tension of said elastic cord until said projectile is displaced by the operator.

2. A toy gun and projectile comprising a 45 projectile, elastic means to act upon said projectile and adapted to propel said projectile, a portion of said body being formed to sustain said projectile against the tension of said elastic means until said projectile is displaced by the operator.

3. A toy gun and projectile comprising a projectile, a gun body, provided with a recess to hold said projectile, an elastic band connected to said gun body and adapted to stretch over said projectile and to propel said 55 projectile when displaced from said recess.

4. A toy gun and projectile comprising a projectile, a gun body adapted to receive said projectile, an elastic cord connected with said gun body and adapted to stretch over said 60 projectile and to propel said projectile, a lug on said body adapted to sustain said projectile against the tension of said elastic cord until said projectile is tipped over said lug by the operator.

5. A toy gun and projectile comprising a projectile, a gun body with seat adapted to receive said projectile, an elastic cord connected with said gun body and adapted to stretch over said projectile and to propel said 70 projectile when said projectile is tipped over the edge of said seat by the operator.

6. A toy gun and projectile comprising a disc shaped projectile, a gun body with seat adapted to receive said projectile, an elastic 75 cord connected with said gun body and adapted to stretch over said projectile and to propel said projectile with a whirling motion when said projectile is tipped over the edge of said seat by the operator.

7. A triggerless toy gun comprising a body member and an elastic member to propel the projectile, the said body member having a recess formed therein and said recess being shaped to hold the projectile in place against the pull of the said propulsive member.

8. A triggerless toy gun comprising a body member and an elastic member to propel the projectile, the said body member having a projectile holding recess formed therein, and 90 the said elastic member being disposed normally to push said projectile into said recess.

NATHANIEL BALDWIN.
